US0D1094762S

(12) **United States Design Patent** (10) Patent No.: **US D1,094,762 S**
 Fontova Sosa et al. (45) Date of Patent: ** Sep. 23, 2025

(54) **CELL THERAPY MANUFACTURING APPARATUS**

(71) Applicant: **GLOBAL LIFE SCIENCES SOLUTIONS USA LLC**, Marlborough, MA (US)

(72) Inventors: **Andreu Fontova Sosa**, Founex (CH); **Nicolas Petitfourg**, Eysins (CH); **Robert Curtis**, Cambridge (GB)

(73) Assignee: **Global Life Sciences Solutions USA LLC**, Marlborough, MA (US)

(**) Term: **15 Years**

(21) Appl. No.: **29/897,819**

(22) Filed: **Jul. 19, 2023**

(30) **Foreign Application Priority Data**

Feb. 13, 2023 (EM) 015011395-0001

CLAIM

The ornamental design for a cell therapy manufacturing apparatus as shown and described.

DESCRIPTION

FIG. 1 is an isometric view of a cell therapy manufacturing apparatus according to an embodiment of the present invention;

FIG. 2 is an end view thereof;

FIG. 3 is an opposite end view thereof;

FIG. 4 is a side view thereof;

FIG. 5 is a top view thereof; and,

FIG. 6 is a bottom view thereof.

The broken lines illustrate portions of the cell therapy manufacturing apparatus that form no part of the claimed design.

1 Claim, 6 Drawing Sheets
